UNITED STATES PATENT OFFICE.

RALPH N. FLINT, OF DETROIT, AND LLOYD BLACKMORE, OF HIGHLAND PARK, MICHIGAN, ASSIGNORS TO GENERAL MOTORS CORPORATION, OF DETROIT, MICHIGAN, A CORPORATION OF DELAWARE.

TRANSMISSION LOCK.

Application filed October 27, 1924. Serial No. 746,067.

This invention relates to transmission locks, and is illustrated as embodied in a sliding-gear selective transmission for an automobile.

An object of the invention is to provide an inexpensive but effective lock for the transmission. In one desirable arrangement, the key-controlled locking bolt is connected to the lever, to move with the lever, and when locked engages a part of the transmission to hold the lever stationary, and preferably in engagement with both of the shifter forks or their equivalents. In the forms shown in the drawings, the lever carries a plate which serves as a guide for the locking bolt, the bolt being movable to engage a stationary plate or the like, or to engage one or both of the shifter forks.

Other objects and features of the invention, including a novel arrangement preventing unauthorized removal of the pedestal carrying the gear-shift lever, and various desirable particular constructions, will be apparent from the following description of the illustrative embodiments shown in the accompanying drawings, in which:

Figure 1 is a vertical longitudinal section through part of one transmission, showing the control lever and the lock in side elevation;

Figure 2 is a horizontal section on the line 2—2 of Figure 1, showing the above-described plates in top plan;

Figure 3 is a vertical section through the plates on the line 3—3 of Figure 2;

Figure 4 is a vertical transverse section through a second transmission, showing the lever and lock in front elevation;

Figure 5 is a horizontal section on the line 5—5 of Figure 4, showing the plates in top plan, and broken away to show the shifter fork rods and to show the yielding pawls in horizontal section;

Figure 6 is a horizontal section on the line 6—6 of Figure 4, showing the mounting of the control lever;

Figure 7 is a vertical longitudinal section through a third transmission, showing the lever and lock in side elevation;

Figure 8 is a horizontal section on the line 8—8 of Figure 7;

Figure 9 is a vertical transverse section through a fourth transmission, showing the lever and lock in front elevation; and

Figure 10 is a horizontal section on the line 10—10 of Figure 9.

Each of the transmissions shown includes a casing 20 inclosing change-speed gearing 22, illustrated as being of the sliding selective type, shifted by shifter forks 24 and 26 having notches 28 for the end of a gear-shifting control lever 30. The forks 24 and 26 are yieldingly held in any selected position by yielding pawls 32, which also serve as an interlock preventing movement of either fork unless the other fork is in neutral. Control lever 30 has a fulcrum pin 34 arranged in sheet metal guides 36 so that it can rock slightly about a central axis, to permit moving the end of the lever from one notch 28 to the other, while it can serve as a fulcrum for gear-shifting movement of the lever. The member 38 is for the support of an emergency brake lever, if one is mounted on the transmission. Except as further described below, these parts or their equivalents may be of any desired construction.

The gear-shifting control lever 30 of the first transmission is universally mounted on a dome or pedestal 40. A part 42, having a concave lower surface fitting over the top of the pedestal, is secured to the lever, as by a pin 44, and a plate 46 on the inside of the pedestal is held against its inner concave surface by a spring 48. The bottom of the pedestal fits within a flange 50 of the casing 20, supported by a ledge 52 and secured to the ledge by bolts or screws 54. A plate 56, having a central opening for the control lever, fits within flange 50 below the pedestal, and is separately secured to ledge 52 by bolts or screws 58. This plate has fingers 60, sprung upwardly to overlap a plate 62 secured to the gearshift lever by a pin or the like 64. Plate 56 and fingers 60 permit plate 62 to move in substantially its own plane, and thus permit universal movement of the gear-shift lever, but prevent withdrawal of the lever and removal of dome 40, even after the removal of bolts or screws 54, by a thief attempting in this manner to secure access to the lock described below. The bottom flange of the pedestal 40 prevents access to bolts or screws 58, and flange 50 prevents prying out the pedestal and plate 56 by means of a cold chisel.

Plate 62 serves as a guide for a vertical-

ly movable locking bolt 66, urged upwardly to unlocked position by a spring 68, and depressible to enter an opening in plate 56 to hold the gearshifting control lever in 5 neutral, and preferably in a position where it projects into both notches 28. The bolt is controlled by a lock barrel 70, operated by a key 72 to withdraw a latch 74 and allow it to seat in either of two recesses 10 76 or 78 formed in part 42. It will be seen that bolt 66 is connected to lever 30 and moves therewith. Barrel 70 is held against angular movement by a stationary pin or projection 80 entering a slot 82 in its side. 15 The transmission shown in Figures 4, 5, and 6 differs from that described above, in that flange 50 of casing 20 is omitted, plate 62 is not pinned to lever 30 but is held in sliding engagement with plate 56 by spring 20 68, and fingers 60 on plate 56 are omitted. In this transmission, also, the lock is at one side of the control lever, instead of behind it. The third transmission (Figures 7 and 8) differs from the first and second, in that 25 bolt 66, instead of entering an opening in plate 56, locks the transmission by entering a recess formed half in each of the shifter forks 24, 26. In the fourth transmission (Figures 9 and 10) the bolt enters 30 a recess in fork 26. In the third and fourth transmissions, plate 62 is directly slidably supported on plane upper surfaces formed on the lever-engaging parts of the shifter forks. 35 While several illustrative embodiments have been described in detail, it is not our intention to limit the scope of the invention to those particular embodiments, or otherwise than by the terms of the appended 40 claims.

We claim:

1. A transmission lock comprising, in combination, change-speed gearing and controlling means therefor including a movable operating lever, a key-controlled locking member adjacent the lever, means connecting said member with the lever so as to cause it to move with the lever, and a part engageable by the locking member to prevent movement of said means, to thereby lock the transmission. 45
2. A transmission lock comprising, in combination, change-speed gearing and controlling means therefor including a movable operating lever, a key-controlled locking member arranged alongside and moving with the lever, a part moving with the lever and which part is constructed and arranged to constrain the locking member to 50 move with the lever without interfering with its locking and unlocking movements, and a part engaged by said locking member to lock the transmission. 55
3. A transmission lock comprising, in combination, a casing and changespeed gear- 60

ing therein, an operating lever extending into the casing to control said gearing and which lever is universally mounted on the casing, a part secured to the lever inside the casing and a part secured to the lever adjacent the point where it passes into the casing, a key-controlled locking member carried by said parts, and means whereby the part aforesaid inside the casing may be locked to an element of the transmission. 70 75

4. A transmission lock comprising, in combination, sliding change-speed gears, shifter forks for moving the gears and which forks have notches which are opposite each other in neutral, an operating lever universally mounted to have its lower end swung into either notch, and key-controlled means to lock the lever and hold it stationary with its end in a central position extending into both notches. 80 85

5. A transmission lock comprising, in combination, gearing and a universally-mounted control lever therefor, a plate secured to the lever to move back and forth and from side to side with the lever, and key-controlled 90 means to lock the plate to a part of the transmission mechanism, to thereby hold the lever positively against movement. 95

6. A transmission lock comprising, in combination, gearing and a universally-mounted control lever therefor, a plate secured to the lever to move therewith, a key-controlled locking bolt carried by the plate, and a stationary plate adjacent and substantially parallel to the movable plate and which has an opening for the locking bolt to prevent movement of the lever when the transmission is locked. 100

7. A transmission lock comprising, in combination, shifter forks and a universally-mounted control lever therefor, a plate secured to the lever to move therewith, and a key-controlled locking bolt carried by the plate, the bolt being engageable with a stationary part to lock the transmission. 105 110

8. A transmission lock comprising, in combination, change-speed gearing and a universally-movable control lever therefor, a housing for the gearing, a plate secured to the lever to move therewith, a stationary plate secured to the housing adjacent and parallel to the movable plate, and a locking bolt guided by one of said plates, the other plate having a locking opening for the bolt, said plates having interengaging portions 115 permitting movement of the lever to control the gearing but preventing separation of the plates. 120

9. A transmission lock comprising, in combination, change-speed gearing and a casing inclosing the gearing, the casing having an opening for a control lever, a plate having an opening and secured to the casing over the opening, a pedestal secured to the casing over the plate, a control lever universally 125 130

mounted on the pedestal and extending through the opening in the plate to control the gearing, and means connecting the lever and plate in a manner permitting movement 5 of the lever to control the gearing but preventing removal of the lever and pedestal in a direction away from the plate.

10. A transmission lock comprising, in combination, change-speed gearing and a casing inclosing the gearing, the casing having an opening for a control lever, a plate having an opening and secured to the casing over the opening, a pedestal secured to the casing over the plate, a control 15 lever universally mounted on the pedestal and extending through the opening in the plate to control the gearing, a second plate carried by the lever, and means connecting the plates in a manner permitting movement 20 of the lever to control the gearing but preventing separation of the plates.

11. A transmission lock comprising, in

combination, a casing having an opening surrounded by a supporting ledge and with a flange surrounding the ledge, change-speed 25 gearing inclosed in the casing, a plate having a central opening and supported on the ledge with its edges protected by the flange, a pedestal seated on the plate with its edges protected by the flange, means to secure the 30 plate and the pedestal to the casing, a control lever universally mounted on the pedestal and extending through the opening in the plate to control the gearing, means to connect the lever to the pedestal, and means 35 to connect the lever and the plate in a manner permitting controlling movement of the lever but preventing withdrawal of the lever, and through the lever preventing removal of the pedestal.

In testimony whereof we affix our signatures.

RALPH N. FLINT.
LLOYD BLACKMORE.
